UNITED STATES PATENT OFFICE.

FRANK L. GORMLEY, OF BROOKLINE, MASSACHUSETTS.

LIFTING-JACK.

1,287,966.

Specification of Letters Patent. Patented Dec. 17, 1918.

Application filed February 21, 1918. Serial No. 218,903.

To all whom it may concern:

Be it known that I, FRANK L. GORMLEY, a citizen of the United States of America, and a resident of Brookline, in the county 5 of Norfolk and State of Massachusetts, have invented certain new and useful Improvements in Lifting-Jacks, of which the following is a specification.

This invention relates to lifting jacks and 10 particularly to devices of this character designed for heavy work, the particular object of the invention being the provision of means whereby the lowering of the movable member under great loads may be easily controlled by hand.

The invention consists in providing the operating gear spindle with locking means which will permit the gear to be rotated in one direction to raise the movable member 20 but will prevent accidental rotation of said gear in the reverse direction, said locking member having associated therewith a manually operated lever for controlling the action of said locking means.

25 The invention further consists of certain novel features of construction and arrangement of parts which will be more fully understood by reference to the description of the drawings and to the claims to be herein- 30 after given.

For the purpose of illustrating the invention one preferred form thereof is illustrated in the drawings, this form having been found to give satisfactory and reliable 35 results, although it is to be understood that the various instrumentalities of which the invention consists can be variously arranged and organized and that the invention is not limited to the precise arrangement and organization of these instrumentalities as herein- 40 shown and described, except as required by the scope of the appended claims.

Of the drawings:

45 Figure 1 represents a horizontal section of a lifting jack embodying the features of the present invention, the cutting plane being on line 1, 1 on Fig. 2.

Fig. 2 represents a vertical section of the same, on line 2, 2 on Fig. 1.

50 Fig. 3 represents a vertical section on line 3, 3 on Fig. 2, drawn to an enlarged scale, and

Fig. 4 represents a horizontal section on line 4, 4 on Fig. 2.

55 Similar reference characters designate like

parts throughout the several figures of the drawings.

In the drawings, 10 represents a suitable base supporting a stationary standard 11, over the outer periphery of which is fitted 60 a movable sleeve 12, to the upper end of which is threaded a cap 13.

In the upper end of the standard 11 is mounted a nut 14 to which is threaded a lifting screw 15 having splined to its upper 65 reduced end a bevel gear 16 with which meshes a bevel gear 17 formed upon or secured to a revoluble shaft or spindle 18, the outer end of which is provided with a suitable operating mechanism 19 of any well 70 known construction.

Between the upper face of the bevel gear 16 and the inner face of the cap 13 are two annular plates 20, 21, between which are interposed a plurality of anti-friction members 22.

The movable member 12 is provided on one side with a flanged projection 24 having a removable plate 25 secured thereto by bolts 26.

80 The plate 25 is provided with a bearing 27 for the spindle 18, and keyed to said spindle 18 between said inner end of said bearing 27 and the rear face of the bevel gear 17 is a worm gear 28 rotatable in either 85 direction with the bevel gear 17.

The worm gear 28 meshes with a worm 29 formed upon or secured to a shaft 30 revolvably mounted in ears 31, 32 projecting 90 inwardly from the plate 25.

95 On one end of the shaft 30 and adjacent to the ear 32 are two collars 33, 34 between which are interposed a plurality of anti-friction members 35, said collars 33, 34 being retained together by a ring 36 secured to the collar 33 and having an annular flange 37 extending over the outer face of the collar 34. The collars 33, 34 with the anti-friction members 35 form a thrust bearing for the shaft 30 on which the said thrust 100 bearing is retained by a nut 38 threaded to the reduced end 39 of said shaft.

Loosely mounted on the opposite end of the shaft 30 is a spur gear 40 having a tapered annular flange 41 with which coacts 105 a disk 42 keyed to the shaft 30 and having a cone-shaped periphery adapted to contact with the tapered flange 41 of the gear 40.

The disk 42 is retained upon the reduced end 43 of the shaft 30 by means of the nut 110

44 threaded to said reduced end. When the movable member 12 is being raised the worm gear will be rotated in the direction of the arrow *a* on Fig. 3 of the drawings and the 5 disk 42 will be separated from the flange 41 and no rotation will be imparted to the spur gear 40.

When a load is on the cap 13 tending to lower the member 12 the tendency would be 10 to rotate the worm gear 28 in a direction opposite to that indicated by the arrow *a* and the worm shaft 30 would be moved endwise, toward the right of Fig. 3, until the cone-shaped periphery of the disk 42 has 15 been brought into firm contact with the tapered flange 41 on the gear 40.

It is obvious that under these conditions any rotary movement imparted to the shaft 30 will be imparted to said gear 40 and 20 through it to the pinion 45 with which its teeth are constantly in mesh.

The pinion 45 is formed upon or secured to one end of a short shaft 46 revolubly mounted in a bearing 47 formed upon the 25 plate 25, said shaft 46 being provided at its end with a reduced portion 48 to which is keyed a brake disk 49 having a cone-shaped periphery.

The plate 25 is provided with another 30 bearing 50 in axial alinement with the bearing 47 and in this bearing 50 is slidably mounted the shank 51 of a disk 52 having a flange 53 the inner wall of which is tapered to fit the cone-shaped periphery of the 35 disk 49.

The flange 53 of the disk 52 is normally held in contact with the periphery of the disk 49 by means of the spring 54 and said disk 52 is prevented from rotating by means 40 of the pins 55 extending therefrom into openings 56 in a flange 57 forming a part of the bearing 50.

This bearing 50 is provided with two 45 diametrically disposed slots 59 in its periphery and in these slots 59 are positioned the cylindrical hubs 60 of a bifurcated lever 61 having cam surfaces 62 bearing against the inner face of the collar 58.

The lever 61 is provided with an arm 63 50 projecting through an opening 64 in the plate 25 the outer end of which is accessible to the operator who may with his fingers move the arm 63 in the direction of the arrow *b* and thus disengage the brake members 49, 53 and thereby permit the member 12 to be lowered.

As long as these brake members 49, 53 are 55 in contact the worm 29 will be prevented from rotating and as a consequence, there can be no downward movement of the member 12.

The rapidity of the lowering of the member 12 may be controlled readily by the movement of the lever 61.

65 The pitch of the threads of the worm 29 is

such that said worm may be rotated by the rotation of the worm gear 28.

In the operation of the jack the worm gear 28 is revolved in the direction of the arrow *a* when raising the load and at the initial 70 movement of said gear 28 it will through the slight end movement imparted to the worm 29 disengage the members 41, 42 so that there will be no brake devices or friction to retard the rotation of the gear 28.

When, under the load, the gear 28 begins to rotate in the opposite direction, the worm 29 will be moved endwise until the members 41, 42 are engaged and then rotary movement will be imparted from the shaft 30 to 80 the short shaft 46 through the gears 40—45. At this time the brake members 49, 53 will be disengaged, said disengagement having been effected by the lever 61.

When, on account of an excessive load 85 upon the cap 13, the member 12 moves downwardly too rapidly, its movement may be arrested by simply moving the lever 61 to bring the members 49—53 into frictional contact.

90 This makes a very simple mechanism for controlling the lowering of the jack and it is believed that its operation and the many advantages of the invention will be readily understood without further description.

95 One advantage of the present invention is that it dispenses with the use of all pawls and ratchets which are ordinarily used in jacks of this character.

Having thus described my invention, I 100 claim:

1. In a lifting jack, the combination of a revoluble operating shaft; a worm gear secured on said shaft and positively rotated thereby in either direction; a worm meshing therewith and adapted to be rotated thereby; and means for retarding the rotary movement of said worm and varying the speed of rotation thereof.

2. In a lifting jack, the combination of a 110 revoluble operating shaft; a worm gear keyed to said operating shaft and positively rotated thereby in either direction; a worm meshing therewith and adapted to be rotated thereby; a brake mechanism; means actuated by the rotation of said worm for placing said brake in action during the lowering operation; and means for controlling the operation of said brake mechanism.

3. In a lifting jack, the combination of a 120 revoluble operating shaft; a worm gear keyed thereto and positively rotated thereby in either direction; a worm meshing therewith and adapted to be rotated thereby; a brake mechanism; means actuated by the rotation of said worm for placing said brake in action during the lowering operation; and manually actuated means for controlling the operation of said brake mechanism.

4. In a lifting jack, the combination of a 130

revolute operating shaft; a worm gear keyed thereto and positively rotated thereby in either direction; a worm meshing therewith and adapted to be rotated thereby and to be moved endwise; a brake mechanism; means including a rotatable member adapted to be placed in action by the end movement of said worm during the lowering operation and thereby actuate said brake mechanism; and means for controlling the operation of said brake mechanism.

5. In a lifting jack, the combination of a revolute operating shaft; a worm gear keyed to said operating shaft and positively rotated thereby in either direction; a worm meshing therewith and adapted to be rotated thereby; a brake mechanism; means including a rotatable member adapted to be placed in action by said worm during the lowering operation and thereby actuate said brake mechanism; and a cam member for controlling the operation of said brake mechanism.

6. In a lifting jack, the combination of a revolute operating shaft; a worm gear keyed to said operating shaft and positively rotated thereby in either direction; a slideable worm meshing therewith and adapted to be rotated thereby; a brake mechanism independent of the slideable worm but actuated by the rotation thereof; means actuated by the sliding movement of said worm for placing said brake in action during the lowering operation; and means for controlling the operation of said brake mechanism.

35 7. In a lifting jack, the combination of a revolute operating shaft member; a movable member thereon; a revolute member for raising said movable member; means for rotating said revolute member including a laterally extending operating shaft; a worm gear keyed to said operating shaft; a worm meshing with and adapted to be rotated by said worm gear and having end movement; a gear loosely mounted on the worm shaft; a member secured to said shaft adapted to be moved with said shaft into driving engagement with said gear; a rotatable brake member; a driving pinion therefor meshing with said gear; and a non-revolute brake member coacting with said rotatable brake member.

8. In a lifting jack, the combination of a revolute operating shelf; a worm gear keyed to said operating shaft; a worm meshing with and adapted to be rotated by said worm gear and having end movement; a gear loosely mounted on the worm shaft; a member secured to said shaft adapted to be moved with said shaft into driving engagement with said gear; a rotatable brake member; a driving pinion therefor meshing with said gear; a non-revolute brake mem-

ber coacting with said rotatable brake member; a spring for normally retaining said brake members in engagement; and manually actuated means for disengaging said members.

9. In a lifting jack, the combination of a revolute operating shaft; a worm gear keyed to said operating shaft; a worm meshing with and adapted to be rotated by said worm gear and having end movement; a gear loosely mounted on the worm shaft; a member secured to said shaft adapted to be moved with said shaft into driving engagement with said gear; a rotatable brake member; a driving pinion therefor meshing with said gear; a non-revolute brake member coacting with said rotatable brake member; a spring for normally retaining said brake members in engagement; and a pivoted cam member for disengaging said members.

10. In a lifting jack, the combination of a revolute operating shaft; a worm gear keyed thereto and positively rotated thereby in either direction; a slideable and rotatable worm meshing with said worm gear; a brake mechanism independent of but adapted to be actuated by the rotation of said worm; and means for placing said brake mechanism in and out of action by the sliding movement of said worm in opposite directions.

11. In a lifting jack, the combination of a revolute operating shaft; a worm gear keyed thereto and positively rotated thereby in either direction; a slideable and rotatable worm meshing with said worm gear; a brake mechanism independent of but adapted to be actuated by the rotation of said worm; means for placing said brake mechanism in and out of action by the sliding movement of said worm in opposite directions; and manually operated means for regulating said brake mechanism when in action.

12. In a lifting jack, the combination of a revolute operating shaft; a worm gear keyed thereto and positively rotated thereby in either direction; a slideable and rotatable worm meshing with said worm gear; a brake disk; means for rotating said disk by the rotation of said worm during the lowering of the load; and a non-revolute member under the control of the operator adapted to coact with said disk to prevent the load being lowered too rapidly.

Signed by me at 4 Post Office Square, Boston, Mass., this 20th day of February, 1918.

FRANK L. GORMLEY.
